UNITED STATES PATENT OFFICE.

FRANCIS BAUMER, OF SYRACUSE, NEW YORK.

DESIGN FOR THE ORNAMENTATION OF CANDLES.

SPECIFICATION forming part of Design No. 14,995, dated May 13, 1884.

Application filed March 31, 1884. Term of patent 7 years.

To all whom it may concern:

Be it known that I, FRANCIS BAUMER, of Syracuse, in the county of Onondaga, in the State of New York, have invented and produced a new Design for the Ornamentation of Candles, of which the following, taken in connection with the accompanying drawing, is a full, clear, and exact description.

The design is fully illustrated in the drawing, wherein *a a* represent star-shaped configurations. *b b* are panels inclosing the said stars, and *c c* are corrugated bands encircling the candle above and below the aforesaid panels.

What I claim is—

1. The design for the ornamentation of candles, consisting of star-shaped configurations

and panels inclosing the same, substantially as described and shown.

2. The design for the ornamentation of candles, consisting of star-shaped configurations, 20 panels inclosing the same, and corrugated bands above and below the panels, substantially as described and shown.

In testimony whereof I have hereunto signed my name and affixed my seal, in the presence 25 of two attesting witnesses, at Syracuse, in the county of Onondaga, in the State of New York, this 20th day of March, 1884.

FRANCIS BAUMER. [L. S.]
